Application October 23, 1930, Serial No. 490,748

34 Claims. (Cl. 179—113)

This invention is a pneumatically-operated loud speaker, of the type employing a current of air under pressure which is passed through a valve, which valve is, in turn, controlled by electrical or other modulations having the characteristics of sound waves. The valve is preferably controlled by an electro-magnetic unit, such as is employed in loud speakers of the magnetic or dynamic type, commonly used today in connection with loud speakers.

The sound reproducer and projector is used particularly in addressing large public gatherings, for example, in a stadium, at a ball park, at a boat race, in a large hall or auditorium, and the like.

The type of valve used to control the air current is, in its broader aspects, known to the prior art, involving a fixed grid or grating through which the air current is passed, in combination with a pivoted grid valve which oscillates back and forth, with the frequency of sound, to impart to the moving air column vibrations having the frequency of sound, which air column amplifies and projects the resulting sound.

With valves of this type the prior art has experienced a great deal of difficulty in that objectionable rattles and other mechanical defects are met with, with the result that the amplified sound is distorted, metallic, and generally unsatisfactory.

This invention is particularly concerned with the control mechanism for the grid valve, involving a mounting and control for the valve which is very finely adjustable which has no rattle or mechanical defects. The adjustment and control of the grid valve must, in this art, be practically micrometric because the difference of a few thousandths of an inch in its position means the difference between success and failure.

The grid valve of this invention may be actuated by any suitable electro-magnetic means. It is particularly designed for use with electrical units of known design, such as the unit used in loud speakers of the "magnetic" and "dynamic" type.

A unit of the magnetic type has an armature which has oscillatory movement to either side of a central or neutral position. The grid valve, however, does not have such movement, but has a semi-dead beat movement, that is to say, a movement from a substantially closed position to open position and back to closed position. Therefore, in actuating the grid valve by means of an armature which has oscillating movement, the armature is connected to the valve so that one

half of its movement actuates the valve, while the other half of its movement is absorbed or damped in such a way that it does not move the valve. According to this invention, a connection is provided which achieves this result. The present preferred type of connection is a flexible link, which when subjected to tension by the armature, pulls the valve open, but which, when subjected to compression, as when the armature moves to the other side of its neutral position, bends or bows and so absorbs this second half of the valve movement.

However, with a unit of the dynamic type which has a movable coil, called the "voice coil", the absorption of one-half of the movement of the coil is not necessary, because the voice coil moves away from and back to its original position, just as the grid valve does.

Where the magnetic unit is used, the movement of the armature is suitably damped, for preventing any rattle. Where the dynamic unit is used, the voice coil is mounted on resilient members, allowing its limited freedom of movement.

The invention will be further described by reference to the accompanying drawings, showing specific embodiments thereof, which illustrate in detail the present preferred ways of carrying out the invention. It should be understood, however, that the invention is not to be limited to these precise details, but may be carried out in other ways. Further advantages of structure and operation will be apparent from the detailed structures now to be described.

 Fig. 22 is a cross section on line 22—22 of Fig. 20.
- Referring now to these drawings in which similar reference characters indicate similar parts, 2 shows the base plate on which is mounted in a supporting frame work indicated generally at 3, an electrical unit of the magnetic type of known design, the details of which form no part of this invention. This unit comprises a horseshoe magnet 4 between the poles of which are coils 6, cooperating with a laminated core 8, all of which serve to actuate an armature 10. The frame work 3 of the magnetic unit is variably positioned with respect to base 2, by means of screws 11, working in slots 12.
- The armature 10 of the magnetic unit is connected to a bridge-member 14, the lower end 30 of which is secured to an arm 16. The armature 10, when in operation, oscillates back and forth, communicating its movement to the bridge member 14. In order to dampen this movement there is provided a small rubber block 18 on one 35 side of the arm 16 and a thicker rubber block 20 on the other side. Variable pressure may be exerted against the rubber block 20 by means of a bridge piece 22 which may be pressed with varying force against the block 20 by means of 40 screws 23 in opposite ends of the piece 22.
- The oscillatory movement of the bridge member 14 serves to open and close a pivoted grid valve 24, which is pivoted to move on knife edges 26. The grid valve is provided with a plurality 45 of narrow preferably parallel slots 25, as is usual in this art. The flat side of the grid valve 24 bears against a fixed grid 28. This general type of grid valve and grid have been used in the prior art, but the results heretofore have been 50 unsatisfactory because of mechanical difficulties, such as rattle and difficulty in adjustments. This valve must be very finely adjusted and must be securely held in the proper adjusted position, yet must be very sensitive and very quick to respond 55 so as accurately to amplify and reproduce the vibrations communicated to it from the armature 10 of the magnetic unit.
- The armature 10 has two-way movement, that is to say, movement to both sides of a central or 60 neutral position. However, the valve 24 does not have such a movement, but has a semi-dead-beat movement, that is to say, a movement from a closed position to an open position and back to the closed position. It is an important aspect 65 of this invention to provide a connection between the armature 10 and the valve so that a movement of the armature 10 to one side of its central or neutral position is communicated to the valve, while its movement to the other side 70 of the central or original position is not communicated to the valve. Such a valve mounting and connection will now be described. The knife edges 26 on which the grid valve pivots are formed in laterally extending arms 30, carried by a plate 75 32 which may be integral with the valves 24, or attached to it as by screws 31. The knife edges 26 of the valve are seated in grooves 34, formed in a plate 36. Plate 36 rests in a recess 37 formed in one side of the air head 38, being held in place by screws 39, proper spacing being had by one or more shims 35. The screws 39 pass through elongated slots 39a in plate 36, so as to enable plate 36 to be adjusted. This plate must be very accurately adjusted. The knife edges 26 are resiliently pressed into the grooves 34 by spring means 40, here shown as a spring plate, one end of which is secured as at 41 to plate 36, while the other end bears directly against the outer end of the plate 32, so that the pressure of the plate 40 tends to move the valve 24 to closed position. The pressure exerted by the spring plate 40 may be varied by means of a screw 40a, threaded into the plate 36.
- Interconnecting valve 24 and bridge 14 is a semi-flexible connecting link 42, the central part 20 of which is flattened so that under compression it will bend or bow a slight amount, but will readily transmit tension. One end, as 43, of the link is rigidly secured to some part of the valve 24, such as the plate 32, while the other end, 25 44, of the link, is soldered to the bridge 14. By reason of this connection, and by reason of the flexibility of the central part 42 of the flexible link, upward movement of the armature 10 and 30 the bridge 14 will exert tension on the link and pull the valve open, while downward movement, below the neutral point of armature 10, will simply cause the connecting link to flex or bend, as shown in dotted lines, Fig. 3, so that the other 35 or downward half of the isochronous movement of the armature 10 is not transmitted to the valve 24.
- The air head 38 is provided with an inlet pipe 50 through which air under suitable pressure is admitted to the interior chamber 52 of the air head. Leading from the central air chamber 52 is a passage 54 which registers with a passage 56 in a relatively thick plate 58. The lower or outer face of the plate 58 is provided with the grid 28 in registry with the passage 56, so that it will be clear that the air under pressure is delivered to the grid, so as to be controlled by the grid valve 24, just below the grid 28. Sealing gasket 60 is provided between plate 58 and the air head 38.
- Cooperating with the air head 38 and plate 58 is a covering plate 62 having an exit pipe 64 for the release or escape of the amplified sound waves. The plates 58 and 62 are recessed as shown at 66 and 68 respectively to accommodate 55 the plate 36 which supports the valve 24. Gasket 60 and plates 58 and 62 are held in assembled relation with each other, and with the air head 38, by means of screws 67 passing through holes 69.
- The plate 62 is further cut-out as at 70, to provide a working space for the valve 24. In order to provide a seal against the escape of air around the base of the valve 24 there is provided a washer or gasket 72 of rubber or the like. It is quite important that no air be allowed to escape around the valve as much volume and efficiency would be thereby lost. The use of this gasket also serves to prevent local vibrations within the valve, which local vibrations, unless damped out, would tend to give a metallic effect to the sound waves.
- It is of importance that the valve 24 be very accurately adjusted with respect to the grid 28, to within a few ten-thousandths of an inch. In 75

order to provide this adjustment the air head 38 is provided with trunnions 74 which are journaled in bearings 74a. The air head 38 may be moved through a very small arc about these trunnions

5 by means of a rod 76, one end of which is finely or micrometrically threaded and engages with a lug 78 on the air head. The other end of rod 76 is rotatably mounted in the base plate 2, and may be manually turned by the knurled head 77, being held against longitudinal movement by the fixed washers 79. There is thus provided a fine or micrometric adjustment for the angular relationship between the air head 38 and the grid valve 24. Upon turning the screw 77, the air

15 head pivots about its trunnions 74, the grid 28 meanwhile maintaining its position, by reason of the fact that it is held in place by the connecting link 42, which in turn is connected to the bridge member 14.

20 The knife edges 26 for the grid valve are directly in the prolongation of the axes of trunnions 74, so that as the air head 38 is moved on the trunnions, the valve 24 maintains its position while the head 38 is moved toward or away from the valve 24, this relative pivotal movement taking place about the knife edges 26, and giving a fine micrometric adjustment between the air head and grid valve.

Reference will now be made to Fig. 7 and succeeding figures showing the use of an electrical unit of the dynamic type. This unit comprises a plate 80 provided with a central passageway 82 to the left side of which air under pressure is delivered from a pipe 84. The other end 30 of the passage 82 is provided with a fixed grid 83, which is controlled by a pivoted grid valve 86 provided with the usual slots 88. This valve is generally similar to the valve 24, and is mounted to rock on knife edges 90. The knife edges 40 90 are variably positionable by any suitable means, such as screws 91 passing through elongated slots 91a in the knife edge block. The inner face of the valve 86 is provided with knife edge receiving grooves 92. In order to hold the valve against the knife edges with a variable resilient pressure, there is provided a rod 94 which passes through a centrally located hole 95 in the valve and so into the plate 80. Spring 96 is interposed between the head of the rod 50 and a freely movable washer 98, so that as the rod is screwed into the plate the spring will be further compressed, thereby exerting greater pressure on the valve. The washer 98 is provided with a knife edge 99, which is seated in a groove 99' in the valve. The knife edges 99 and 98 are in the same straight line so that while the valve is firmly held there are no unbalanced forces that would tend to move it in either direction, whereby the valve is highly 55 sensitive and nicely balanced and so will move readily in either direction.

In contradistinction to the valve 24 of Fig. 2, which is actuated from the pivoted end, the valve 86 of this modification is actuated from the end or side opposite the pivot. The valve 86 is therefore provided with a lug 100, having a hole in which is secured an actuating link 102 which passes through a slot 103 in the plate 80. In order to compensate for the slight arcuate movement of the upper end of the valve 86 the connecting link 102 is flattened at its central part so as to be resilient, whereby it can readily accommodate itself to this small arcuate movement. A flexible diaphragm 101 fits tightly around rod 102, and has its peripheral edges

sealed against plate 80, whereby link 102 can oscillate back and forth without allowing any escape of air through slot 103.

The actuating link member 102 is operatively connected to the voice coil of an electrical unit of the type known as the dynamic type of loud speaker. The voice coil of such unit is shown at 104. This voice coil is mounted in a hole in plate 106, made in two parts for convenience in assembly and just clearing the end of the main 10 coil 108. Each side of the voice coil is secured to supporting spiders 110 and 111, having arms 112 which are carried by the pole pieces 106. The supporting arms 112 are resilient, so as to permit the voice coil to oscillate freely when subjected to a varying magnetic field from coil 108.

The outer spider 110 is provided with a plurality of converging arms 114 which connect this spider to the actuating link 102, so that the movements of the voice coil are communicated 20 through 102 to the valve 86. It will be understood that the central coil 108 of the dynamic unit is supplied with a current having the characteristics of sound waves, which may be produced in any of the known ways, as by microphone, phonograph, telephone, or any other suitable source.

With the dynamic unit thus described the movement of the voice coil has what is substantially a semi-deadbeat movement, that is to 30 say, it moves from the original position outwardly to a maximum position and then back to the original position, without moving to the opposite side, as is the case with the magnetic unit. This being so, all movements of the voice coil 35 can be and are transmitted to the valve 86 without damping out half of such movement as was described in connection with Figs. 1, 2 and 3.

Figures 13 and 14 show a modified form of valve mounting which could be used in connection with either the dynamic or the magnetic unit. In this modification the grid valve 116 provided with the usual slots is provided with a plate 118, carried by and secured to the base of the valve which could be integral with the valve 45 if desired. This plate is provided with extensions 120. The outer side of the extensions 120 are provided with knife edges 122 (see Fig. 15) to one side of the center, and toward the valve. Bearing against the knife edges 122 is a pair of 50 springs 124 which are secured to the plate 80 by rivets 126. The force of the springs can be varied by screws 128 passing through them into plate 80.

The central part of plate 118 is provided with a knife edge 130 which is offset in the opposite direction with respect to knife edges 122, the result of which is that the spring has a leverage on the valve equal to the distance between the offset knife edges, whereby the spring will tend 60 to rock the valve to a closed position. The knife edges 130 are seated in grooves 131 in the studs or standards 132. The knife edges are variably positionable by having the standards 132 variably positionable. This is effected by providing standards 132 with elongated slots 133, through which pass suitable mounting screws 133a, like the screws 91 of Fig. 11.

The plate 118 is provided with a connecting link 134 which is connected to the rod 102, which 70 is actuated by the voice coil 104 of Fig. 7. Link 134 could also be connected for actuation by link 43 of the magnetic unit.

Referring now to Fig. 16, the dynamic unit comprising the coil 108 and voice coil 104 are 75

substantially the same as in Fig. 7; so also with the plate 80 and grid valve 86 mounted on its knife edges. Air is admitted to the grid, controlled by the valve 86, through the pipe 140. In this modification the voice coil is provided with a rod 142 which is connected to a resilient lever arm 143, the lower end of which is suitably secured to a member such as 148, at 144. The voice coil could be connected to rod 142 by a spider 114, as shown in Fig. 7, if desired. A rod 146 passes loosely through an opening 147 in the plate 80 and is flexibly connected to lug 100 at the top edge of the valve 86. The rod 146 has sufficient flexibility to compensate for the very slight arcuate movement of the top of the valve. Escape of air through 147 is prevented by a flexible diaphragm 146a through which 146 passes. In order to dampen the movements of the voice coil and lever arm 143, there is provided a screw 148, variably positionable in plate 80; this screw carries rubber blocks 149 and 150, variably positionable by nuts 151 threaded onto the screw 148.

In this form of the invention, oscillation of the voice coil causes corresponding pivotal movement of the valve 86 with resultant impression on the air current passing through the grid of the characteristics that have been impressed on the voice coil.

In the modification shown in Fig. 19, the grid is composed of radially extending slots 152 while the grid valve 154 is provided with radially extending slots 156 which are adapted to go into and out of registry with the slots in the grid when moved about its pivot 158 toward which the slots converge. This fan type of grid valve is provided with an actuating link 160 connected to a bridge 162 which is adapted to be actuated by an electrical unit of a magnetic type as shown in Fig. 2 or the dynamic type as shown in Fig. 16.

In the modification shown in Figs. 20, 21 and 22, the grid and grid valves are made in the form of two telescoping tubular members, preferably circular in cross-section. In this modification, casing 166 is provided with an inlet pipe 168 for the admission of air under pressure. Mounted within the casing 166 is a tubular member 170, preferably cylindrical, and open at one end as shown. A partition 172 is mounted air tight in the casing so as to direct the air to the inside of the cylinder.

In the side of the cylinder 170 is a plurality of grid slots 174. Mounted to oscillate within the cylinder is a tubular valve member 176 provided with slots 178 which are adapted to register with the slots 174. Additional or duplicate slots could be provided in other corresponding parts of the cylinder and valve as desired. The valve cylinder 176 may be split longitudinally as at 180 so that it will, aided by the air pressure, expand outwardly into close contact with the inside of the cylinder.

One of the tubular members 170 or 176 is oscillated with respect to the other so as to bring the slots into and out of registry. This oscillation is effected by some suitable electrical means, such as the electrical unit used in a loud speaker of the magnetic type as shown in Fig. 1 or the electrical unit used in a loud speaker of the dynamic type, as shown in Figs. 7 or 16. As shown, the valve 176 is provided at one end with arms 182 which are connected to a rod 184 which passes out of casing 166 and is connected to the armature 184 of the electrical unit. In order to prevent the escape of air through the opening

through which 182 passes, there may be a flexible diaphragm valve 186, the edges of which are sealed against the casing.

The air current, after having been subjected to the modulations imposed on it from the valve 176, passes out of casing 166 through an opening such as 188 into an amplifying horn or the like 190.

The movement of the rod 182 and armature 184 may be damped in any suitable way as for example by rubber blocks analogous to the rubber blocks 148 as shown in Fig. 16.

While various ways of carrying out the invention have been described in detail, it should be understood that the invention is not to be limited to these details, but may be carried out in other ways.

We claim as our invention:

1. In a pneumatic loud speaker, in combination, a pivoted valve, an actuating armature, and a connecting link operatively connecting said valve and armature, said link serving to transmit tension to pull the valve open, but flexing slightly under compression.

2. In a pneumatic loud speaker, in combination, a pivoted valve, an actuating armature, and a link for operatively connecting said valve and armature, said link having a central portion which transmits tension and bends under compression, and having offset portions at opposite ends of said central portion for connection, respectively, to the valve and armature.

3. In a pneumatic loud speaker, in combination, a grid having a flat face, a pivoted grid valve having a flat face adapted to bear against the grid, an actuating armature, means for damping the movement of the armature, and means interconnecting the valve and armature which transmits tension to pull the valve open and which bends under compression when the valve bears against the grid.

4. In a pneumatic loud speaker, in combination, a grid, a grid valve, knife edge means for pivotally mounting the valve and means for variably positioning the knife edges, including slots in the knife edge means and screws passing through said slots.

5. In a pneumatic loud speaker, in combination, a grid, a grid valve, knife edge means for pivotally mounting the valve, spring means for urging the valve toward the grid, and means for variably positioning the knife edges, including slots in the knife edge means and screws passing through said slots.

6. In a pneumatic loud speaker, in combination, a pivoted valve, knife edge means for pivotally mounting the valve, means for variably positioning the knife edge means, an operating unit having an armature, and means operatively connecting the valve and armature, which transmits tension, and flexes under compression.

7. In a pneumatic loud speaker, in combination, a pivoted valve, knife edge means for pivotally mounting the valve, means for variably positioning the knife edge means, spring means for urging the valve in one direction, an operating unit having an armature, and means operatively connecting the valve and armature, which transmits tension, and flexes under compression.

8. In a pneumatic loud speaker, in combination, an air head, means for pivotally mounting the air head, a grid carried by the air head, a grid valve cooperating with the grid, knife edge means for pivotally mounting the valve, and

- means for varying and maintaining the relative angular setting between the air head and the grid valve.
9. In a pneumatic loud speaker, in combination, an air head, means for pivotally mounting the air head, a grid carried by the air head, a grid valve cooperating with the grid, knife edge means for pivotally mounting the valve, spring means for urging the valve in one direction, and screw threaded means for varying and maintaining the relative angular setting between the air head and the grid valve.
10. In a pneumatic loud speaker, in combination, a pivotally mounted air head, a grid carried thereby, a grid valve pivotally mounted with respect to the grid, the pivotal axis of the air head and the pivotal axis of the valve being in substantially the same straight line, and means for micrometrically varying the relative setting between the air head and the grid valve.
11. In a pneumatic loud speaker, in combination, a pivotally mounted air head, a grid carried thereby, a grid valve pivotally mounted with respect to the grid, knife edge means on which the valve pivots, the pivotal axis of the air head and the pivotal axis of the valve being in substantially the same straight line, and means for micrometrically varying the relative setting between the air head and the grid valve.
12. In a pneumatic loud speaker, in combination, a pivotally mounted air head, a grid carried thereby, a grid valve pivotally mounted with respect to the grid, knife edge means on which the valve pivots, spring means for pressing the knife edges toward their seats, the pivotal axis of the air head and the pivotal axis of the valve being in substantially the same straight line, and means for micrometrically varying the relative setting between the air head and the grid valve.
13. In a pneumatic loud speaker, apparatus adapted to be operated by the voice coil of an electrical unit of the dynamic type, including in combination a grid, a pivoted grid valve, coil means for operating the grid valve engageable with the valve at one end thereof, and knife edge means for pivotally mounting the grid valve at the opposite end thereof.
14. In a pneumatic loud speaker, apparatus adapted to be operated by the voice coil of an electrical unit of the dynamic type, including in combination a grid, a pivoted grid valve, coil means for operating the grid valve, engageable with the valve at one end thereof, knife edge means for pivotally mounting the grid valve at the opposite end thereof and means for variably positioning said knife edge means.
15. In a pneumatic loud speaker, apparatus adapted to be operated by the voice coil of an electrical unit of the dynamic type, including in combination a grid, a pivoted grid valve, coil means for operating the grid valve, engageable with the valve at one end thereof, knife edge means for pivotally mounting the grid valve at the opposite end thereof and means for exerting a variable pressure on said knife edge means.
16. In a pneumatic loud speaker, in combination, a grid, a grid valve pivoted near one edge, and actuating means attached to the grid valve along the edge opposite the pivot so as to be outside the air stream.
17. In a pneumatic loud speaker, in combination, a grid, a grid valve pivoted near one edge, actuating means attached to the grid valve along the edge opposite the pivot so as to be outside the air stream and spring means for urging the valve toward closed position.
18. In a pneumatic loud speaker, in combination, a grid, a grid valve, a knife edge mounting at one side of the valve for pivotally mounting it, and means, attached to the side of the valve opposite the knife edge mounting, for actuating the valve.
19. In a pneumatic loud speaker, in combination, a grid, a grid valve, a knife edge mounting at one side of the valve for pivotally mounting it, means for variably positioning said knife edge mounting, and means, attached to the side of the valve opposite the knife edge mounting, for actuating the valve.
20. In a pneumatic loud speaker, in combination, a grid, a grid valve, a knife edge mounting at one side of the valve for pivotally mounting it, means, attached to the side of the valve opposite the knife edge mounting, for actuating the valve and spring means for urging the valve toward the closed position.
21. In a pneumatic loud speaker, in combination, a grid, a grid valve, a knife edge mounting at one side of the valve for pivotally mounting it, means for exerting a variable resilient pressure on said knife edge mounting, and means, attached to the side of the valve opposite the knife edge mounting, for actuating the valve.
22. A grid valve, pivotal mounting means carried by said valve and attached to the base of the valve, said pivotal mounting means comprising laterally displaced knife edges, and spring means bearing against one of said knife edges for pivotally rocking the valve and thereby urging it toward closed position.
23. A grid valve, pivotal mounting means carried by said valve and attached to the base of the valve, said pivotal mounting means comprising laterally displaced knife edges, means for variably positioning the knife edges, and spring means bearing against one of said knife edges for pivotally rocking the valve and thereby urging it toward closed position.
24. In a pneumatic loud speaker, a grid and cooperating grid valve, the slots in the grid and grid valve converging in the same direction, the valve being pivoted to oscillate back and forth in its own plane.
25. In a pneumatic loud speaker, a grid and cooperating grid valve, the slots in the grid and the valve converging toward a common center, and a pivot for mounting the valve, located at substantially said common center, the valve oscillating back and forth in its own plane.
26. In a pneumatic loud speaker, in combination, a slotted grid, a cooperating slotted grid valve, pivoted to move toward and away from one face of the grid, spring means for urging the valve toward one face of the grid, a flexible actuating link connected to the valve, tension on which opens the valve, and compression on which bends the link without actuating the valve.
27. In a pneumatic loud speaker, in combination, a grid, a cooperating valve, means for pivotally mounting the valve, spring means for urging the valve toward the grid, whereby the valve travels to one side only of its position of rest against the grid, electrically operated actuating means which oscillates to both sides of its position of rest, and a link connecting said actuating means to said valve which transmits tension to open the valve when the actuating means moves in one direction, but which bends under compression.

sion to absorb the movement of the actuating means when it moves in the opposite direction.

28. In a pneumatic loud speaker, in combination, a slotted grid, a cooperating slotted grid valve, knife edge means for pivotally mounting the valve, spring means for urging the valve toward the grid, whereby the valve travels to one side only of its position of rest against the grid, and a link for actuating said valve, which link transmits tension to open the valve, and which bends under compression.

29. In a pneumatic loud speaker, in combination, a slotted grid, a cooperating slotted grid valve, knife edge means for pivotally mounting the valve, spring means for urging the valve toward the grid, whereby the valve travels to one side only of its position of rest against the grid, a link for operating said valve, which transmits tension to open the valve but which bends under compression, and means for varying the initial setting of the grid and its valve with respect to each other.

30. In a pneumatic loud speaker, in combination, a hollow air head provided with a slotted grid, a valve cooperating with said grid, means for pivotally mounting said valve, means for pivotally mounting said air head, means for angularly positioning the air head about its pivot and holding it set in fixed position, with respect to the valve, and means for connecting the valve with an actuating unit.

31. In a pneumatic loud speaker, in combination, a hollow air head provided with a slotted

grid, a valve cooperating with said grid, knife edge means for pivotally mounting the valve, means for pivotally mounting said air head, means for angularly positioning the air head about its pivot and holding it set in fixed position, and an actuating link, which transmits tension and bends under compression, for connecting said valve with an actuating unit.

32. In combination, a base plate having an air passage therethrough provided with a grid across said passage, a slotted or grid valve pivoted by knife edge means to the base plate, in cooperative relation with the grid, and means passing through the base plate for operating the grid valve.

33. In combination, a base plate having an air passage therethrough provided with a grid across said passage, a valve pivoted to the base plate at one side of the passage in cooperative relationship with the grid, and a valve actuating rod passing through the base plate and attached to the valve at the side opposite its pivot.

34. In combination, a base plate having an air passage therethrough provided with a grid across said passage, a grid valve resiliently pivoted by knife edge means to the base plate at one side of the passage, in cooperative relationship with the grid, and a valve actuating rod passing through the base plate and attached to the valve at the side opposite its pivot.
